UNITED STATES PATENT OFFICE

CLEMENT BOOTH, OF CINCINNATI, OHIO, ASSIGNOR TO CINCINNATI GRINDERS INCORPORATED, OF CINCINNATI, OHIO, A CORPORATION OF OHIO

GRINDING MACHINE

Application filed August 28, 1930. Serial No. 478,419.

This invention relates to improvements in machine tools and especially to improvements in centerless grinders.

One of the principal objects of the present invention is the provision of an improved mechanism for use with a standard centerless grinder for placing in and removing a work piece from the throat thereof.

Another object of the invention is the provision of an improved loading and ejecting mechanism for use in presenting work pieces, such as large spherical objects, billiard balls, or the like, to and removing same from the throat of a centerless grinder.

15 A further object of the invention is the provision of a semi-automatic centerless grinder for expeditiously finishing normally difficult to handle work pieces for increasing the production thereof and reducing their cost to a minimum.

Other objects and advantages of the present invention should be readily apparent by reference to the following specification considered in conjunction with the accompanying drawings, and it is to be understood that any modifications may be made in the exact structural details there shown and described, within the scope of the appended claims, without departing from or exceeding the 30 spirit of the invention.

In the drawings:

Figure 1 is a front elevational view of a machine embodying the improvements of this invention.

35 Figure 2 is a fragmentary end elevation of the machine shown in Figure 1 as seen on line 2-2 thereon.

Figure 3 is a sectional view taken transversely of the machine as seen from line 3-3 40 of Figure 1.

Figure 4 is a sectional view taken on line 4-4 of Figure 3.

Figure 5 is a sectional view taken on line 5-5 of Figure 3.

45 Figure 6 is a vertical sectional view of the hydraulic valve used with this invention.

Figure 7 is an enlarged view of the throat of a centerless grinder showing the work in position between the wheels thereof.

50 Figure 8 is a diagrammatic view of the

opposed grinding and regulating wheels having the work therebetween.

Throughout the several views of the drawings similar reference characters are employed to denote the same or similar parts.

The machine as shown in Figure 1 comprises a bed 10 having fixed at one end thereof for rotation a grinding wheel 11 rotatable at a high or grinding rate of speed in a clockwise direction as indicated by the arrow on its housing 12. Opposed to the grinding wheel 11 is a regulating wheel 13 rotatable in a clockwise direction at a relatively slow work controlling rate of speed and is enclosed within a housing 14 forming part of the regulating wheel unit 15. The active peripheral faces of the wheels 11 and 13 are respectively formed with grooves 16 and 17 as seen in Figure 8, and the said wheels are spaced from one another to form a grinding throat therebetween conforming substantially to the ultimate size and shape to be given to the work 18. As shown in Figure 8, the grinding wheel 11 rotates in a plane normal to the axis of its supporting spindle 19, while the regulating wheel 13 rotates in a plane at an angle to the axis of rotation of its supporting spindle 20, while the grooves 16 and 17 rotate in parallel planes tandem to one another. By this construction the grinding wheel groove 16 is flanked on opposite sides thereof by uninterrupted flanges 21 and 22, while the regulating wheel groove 17 is flanked by interrupted flanges 23 and 24. The inner operative faces of the flanges 23 and 24 act as cams for rotating the work 18 about a multiplicity of axes, the said interrupted flanges exerting a rotation thrust first in one direction and then in the opposite direction.

The regulating wheel unit 15 is formed integral with a slide 25 translatable relative to a second or lower slide 26, supported by and movable relative to ways 27 formed on bed 10. Clamp mechanisms 28 and 29 are provided for respectively securing the upper slide 25 and regulating wheel unit 15 to the lower slide 26 for movement therewith and for clamping the said lower slide 26 to the bed 10. The inner end of the slide 26 is provided

with a block 30 supporting a work rest blade 31 for the work 18. The said block 30 is therefore positioned directly beneath the grinding throat. To feed the work 18 into the 5 grinding wheel 11 to effect a stock removal therefrom, the regulating wheel unit 15 is actuated toward the said grinding wheel. For this purpose an adjusting screw 32 is provided having one end in threaded engagement with a nut 33 carried by the unit 15, and on its opposite end with a pilot or hand wheel 34 for effecting said rotation, the adjusting screw 32 being rotatably, but not translatable, journaled in a bracket 35 secured to the bed 10.

10 The pilot or hand wheel 34 is utilized for adjusting the grinding and regulating wheels relative to one another for initially setting up the machine to adjust the grinding throat to the ultimate size of the work piece to be produced. In practice and for opening and closing the throat to permit the insertion and withdrawal of the work, there is provided a manually actuatable infeed lever 36 having its 15 lower end 37 secured to the nut 33. The said lever is in the position shown in Figures 1 and 2 for opening the grinding throat to permit the insertion of the work, whereupon said lever is actuated to the left, or in a counterclockwise direction, as seen in Figure 2, for actuating the regulating wheel 13 toward the grinding wheel 11. While the grinding throat is expanded or widened, the finished work piece 18 is replaced by an unfinished 20 one by means now to be described.

25 The work rest block 30 has secured thereto on one side of the grinding throat a bracket 37 having a flange 38 at one end thereof resting upon the block 30. A cylinder 39 has one 30 end secured to the flange 38 and its other end secured by lock nut 40 to a lug or arm 41 extending from the bracket 37. A piston 42 is enclosed within the cylinder 39 for movement axially therethrough. A piston 45 rod 43 extends from the piston 42 beyond packing glands 44, secured to the arm 41 at the upper end of the cylinder 39. The upper end of the piston rod 43 is secured by lock nuts 45 to bracket 46 extending from 50 carrier slide 47. The said slide 47 has extending from the opposite ends guides 48 and 49 received in guideways formed by guide member 50 and front plates 51. The guide 55 50 is integral with and extends from the bracket 37 for guiding the slide or carriage 47 during its vertical movements by the piston 42 and piston rod 43.

50 A port 52 communicates with the lower end of the cylinder 39, and a second port 53 communicates with the upper end thereof. A conduit or pipe 54 extends from the port 52, while a similar conduit or pipe 55 extends from the port 53, the said conduits respectively terminate at opposite sides 56 and 57 60 of a three way valve 58. Opposed sides 59

and 60 of the valve 58 communicate respectively with the exhaust and pressure source of an hydraulic system. As shown in Figure 6 the pressure side 60 of the valve 58 is connected with conduit 55 extending to 70 the upper end of the cylinder 39, while the lower end of said cylinder is connected to conduit 54 with the exhaust side 59 of the said valve 58.

75 For supporting the work, or spherical articles, and carrying same into and from the grinding throat, the slide or carriage 47 has extending therefrom pins 61 and 62 extending through the upper and lower ends of arms 63 and 64. The said arms are respectively provided at their lower ends with fingers 65 and 66 each having a tapered upper surface 67 and 68 forming a pocket for the work or ball 18. The arms 63 and 64 are securely pinned or otherwise secured to the pins 80 61 and 62. As shown in Figure 3, the work carrying pocket does not support the work during the actual grinding operation, but merely carries the work to the work rest blade 31 for positioning same thereon. To prevent 85 inadvertent contact between the work or ball and the wheels, guide members 69 and 70 are provided, the former being adjacent the grinding wheel, while the latter is adjacent the regulating wheel, and each are provided 90 at their lower ends with tapered surfaces 71 and 72 to clear the active faces of the grinding and regulating wheels and guide the ball or work to the actual point of grinding. The 95 said guiding arms or fingers 69 and 70 are 100 secured by bolts or the like 73 to the forked ends 74 of a bracket member 75, secured to an upstanding bracket 76, in turn carried by the work supporting block 30.

105 For controlling the flow of the hydraulic pressure through the valve 58, it is provided with a key or cock 77 having connecting ports 78 and 79 formed therein, the former connecting the intake or pressure side 60 of the valve 58 with either of the conduits 54 and 55, while the latter connects either of said conduits with the exhaust side 59 of the valve 58. The key 77 is provided with the usual operating portion 80 secured to which is a lever 81 having its lower end connected by 110 link 82 with an arm 83, see Figure 3. The arm 83 is keyed to, for movement with, a stub shaft 84 rotatably journaled in an extension 85 of the work rest block 30. A rack pinion 86 is keyed or otherwise secured to the shaft 84 for rotating said shaft, and meshes with a rack bar 87 slidably journaled in bearings 88 and 89 extending from the work rest block 30. The outer end of the rack bar 87 has secured thereto a block 90 having a vertical groove 91 formed therein for a roller 92 carried by arm 93 fast on the inner end of rock shaft 94. The other end of the said rock shaft 94 carries a pinion 95 having its teeth meshed with rack 96 on slide bar 97. 115 120 125

The other end of the bar 97 is provided with a notch 98 receiving pin 99 extending from the oscillatable manual infeed lever 36.

The complete operation of the improved mechanism is as follows: assuming the parts to be in the position shown in the drawings with a work piece in the throat and resting on the angle top of the work rest blade 31. Infeed lever 36 would be actuated in a counter-clockwise direction, as seen in Figure 2, which would rotate the nut 33 causing a translating movement of the upper slide 25 relative to the lower slide 26, feeding the work piece or ball 18 into the grinding wheel for effecting a stock removal therefrom. The regulating wheel 18 would control the rotation of the ball and, through the interrupted flanges or cams 23 and 24, cause a rotation of the said ball about a multiplicity of axes, thereby presenting the entire surface of the work or ball to the action of the grinding wheel. After the lever 36 has reached the limit of its movement, the wheels are momentarily held against further travel, permitting a sparking out of the grinding wheel and to produce the desired finish on the work. The lever 36 is then returned to the position shown in Figures 1 and 2, which through the slide lever 97 and coupling 96-95 actuates the key or cock 77 of the valve 58 for connecting the hydraulic pressure with the lower end of the cylinder 39 for raising the piston in said cylinder and carriage 47 thereby lifting the work or ball to the position shown in dotted lines in Figure 3, whereupon the said work or ball 18 may be lifted from the pocket formed at the lower ends of the arms 63 and 64 and an unfinished work piece placed therein. The lever 36 is then again actuated in a counter-clockwise direction for first shifting the valve to connect the hydraulic pressure through the cock 77 with the conduit 55 lowering the piston 42 and carriage 47 to place the work 18 on the angle top of the work rest 31. Continued movement of the lever 36 again feeds the second ball into the grinding wheel 11. The operation of the machine continues by first actuating the lever 36 in one direction and then in the other whereby the work is automatically lowered into the throat, reduced to the desired size, finished in the throat and raised therefrom.

From the foregoing it will be evident that an improved semi-automatic centerless grinder for the production of large spherical work pieces, such as balls for roller bearings, billiard balls, or the like has been produced.

What is claimed is:

1. In a device of the class described the combination with a pair of opposed grinding and regulating wheels forming a grinding throat therebetween, and a work rest

blade within the throat supporting the work for simultaneous engagement with the wheels, of means for placing the work on the work rest blade and removing same therefrom comprising a vertically shiftable carrier, a pair of arms carried by the carrier having fingers at one end thereof for supporting the work during movement toward and from the work rest blade, and means for effecting movement of the carrier. 70

2. In a device of the class described the combination with a pair of opposed grinding and regulating wheels forming a grinding throat therebetween, and a work rest blade within the throat supporting the work for simultaneous engagement with the wheels, of means for placing the work on the work rest blade and removing same therefrom comprising a vertically shiftable carrier, a pair of arms carried by the carrier having fingers at one end thereof for supporting the work during movement toward and from the work rest blade, means for effecting movement of the carrier, and means for actuating one of the wheels toward the other 80 to feed the work on the blade into the grinding wheel. 85

3. In a device of the class described the combination with a pair of opposed grinding and regulating wheels forming a grinding throat therebetween, and a work rest blade within the throat supporting the work for simultaneous engagement with the wheels, of means for placing the work on the work rest blade and removing same therefrom comprising a vertically shiftable carrier, a pair of arms carried by the carrier having fingers at one end thereof for supporting the work during movement toward and from the work rest blade, means for effecting movement of the carrier, means for actuating one of the wheels toward the other to feed the work on the blade into the grinding wheel, and means coupling the wheel moving means and carrier moving means 100 for sequential operation. 105

4. In a device of the class described the combination of a pair of opposed grinding and regulating wheels forming a grinding throat therebetween, a work rest blade subtending the grinding throat for supporting a work piece for simultaneous engagement with the said wheels, a vertically shiftable carrier for positioning work on the blade and removing it therefrom comprising a pair of arms carried thereby, each having its one end extending toward the other to form a work carrying pocket, means for hydraulically, vertically shifting the carrier, and means adjacent the opposed active faces of the wheels cooperating with the work carrying arms to form a work guiding chute to prevent inadvertent engagement between the work and wheels. 115 120 125

5. In a machine for grinding spherical articles the combination of a pair of opposed grinding and regulating wheels forming a grinding throat therebetween, each of the 5 wheels having a groove therein conforming substantially to the contour to be produced on the work, one of said wheels having an interrupted flange flanking its groove whereby the work is rotated about a plurality of 10 axes for presenting its entire surface to the grinding wheel, a work rest blade within the grinding throat for supporting the work during the grinding operation, means vertically shiftable relative to the grinding throat for 15 placing work on the work rest blade and removing same therefrom, and guide means adjacent the opposed active faces of the wheels forming a work guiding chute to prevent inadvertent engagement between the work and 20 wheels.
6. In a device of the class described the combination of a pair of opposed grinding and regulating wheels forming a grinding throat therebetween, a work rest blade within 25 the throat for peripherally supporting work therein, a vertically shiftable carrier adjacent the grinding throat for placing in and removing work therefrom comprising a bracket, a cylinder carried by the bracket, a 30 piston within the cylinder operatively coupled with the carrier, conduits extending from opposite ends of the cylinder, a source of hydraulic pressure and a three-way valve for alternately connecting the pressure 35 source and exhaust with the conduits for alternately raising and lowering the carrier.
7. In a device of the class described the combination of a pair of opposed grinding and regulating wheels forming a grinding 40 throat therebetween, a work loading and ejecting mechanism for placing in and removing work from the grinding throat comprising a block beneath the said throat, a work rest blade carried thereby for supporting the 45 work while in engagement with the wheels, a bracket on the block forming a vertical guide, a carrier movable vertically of the throat through the guide for placing on and removing work from the work rest blade, 50 arms supported by the carrier each having its one end turned toward the other to form work carrying fingers, and means for vertically shifting the carrier.
8. In a device of the class described the 55 combination of a pair of opposed grinding and regulating wheels forming a grinding throat therebetween, a work loading and ejecting mechanism for placing in and removing work from the grinding throat comprising a block beneath the said throat, a work rest blade carried thereby for supporting the 60 work while in engagement with the wheels, a bracket on the block forming a vertical guide, a carrier movable vertically of the 65 throat through the guide for placing on and removing work from the work rest blade, arms supported by the carrier each having its one end turned toward the other to form work carrying fingers, means for vertically shifting the carrier, and means for preventing premature engagement of the work with the wheels.
9. In a device of the class described the combination of a pair of opposed grinding and regulating wheels forming a grinding 70 throat therebetween, a work loading and ejecting mechanism for placing in and removing work from the grinding throat comprising a block beneath the said throat, a work rest blade carried thereby for supporting the work while in engagement with the 75 wheels, a bracket on the block forming a vertical guide, a carrier movable vertically of the throat through the guide for placing on and removing work from the work rest blade, arms supported by the carrier each having its one end turned toward the other to form work carrying fingers, means for vertically shifting the carrier, a second bracket on the block, guide means carried by the second bracket cooperating with the carrier arms forming a work guiding chute for guiding the work to and from the work rest blade and for preventing premature engagement of the work with the wheels.
10. In a device of the class described the combination with a pair of opposed grinding and regulating wheels forming a grinding 80 throat therebetween, a work rest blade subtending the grinding throat for supporting the work while in engagement with the wheels, a vertically shiftable carrier for placing work pieces on the blade and removing same therefrom including a pair of arms supported thereby and having their ends turned toward one another forming work supporting fingers, hydraulic means for effecting the vertical movement of the carrier 85 including an oscillatable three-way valve, guide means cooperating with the work carrying arms forming a work guiding chute, means for feeding one of the wheels toward the other to feed the work into the grinding wheel and effect a stock removal therefrom comprising a manually shiftable lever, and means operable by said lever for oscillating the valve and effecting a shifting movement of the carrier in sequential order with the 90 movement of the lever.
11. In a device of the class described the combination with a pair of opposed grinding and regulating wheels forming a grinding 95 throat therebetween, a work rest blade 100

- subtending the grinding throat for supporting the work while in engagement with the wheels, a vertically shiftable carrier for placing work pieces on the blade and removing same therefrom including a pair of arms supported thereby and having their ends turned toward one another forming work supporting fingers, hydraulic means for effecting the vertical movement of the carrier including an oscillatable three-way valve, guide means cooperating with the work carrying arms forming a work guiding chute, means for feeding one of the wheels toward the other to feed the work into the grinding wheel and effect a stock removal therefrom comprising a manually shiftable lever, means operable by said lever for oscillating the valve and effecting a shifting movement of the carrier in sequential order with the movement of the lever, said means comprising a rock shaft, a slide rod connected with the oscillatable valve, and an operative coupling between the rock shaft and slide rod for converting the oscillations of the rock shaft into reciprocations of the slide valve.
12. In a mechanism for feeding and ejecting spherical or other formed work pieces relative to the throat of a centerless grinder the combination of a vertically movable carrier, supporting pins carried thereby, arms spacedly secured to the pins a distance corresponding to the size of the work, fingers extending toward one another formed on adjacent ends of the arms and forming a work support, and guide means cooperating with the arms and forming therewith a work guiding chute.
13. In a mechanism for feeding and ejecting spherical or other formed work pieces relative to the throat of a centerless grinder the combination of a vertically movable carrier, supporting pins carried thereby, arms spacedly secured to the pins a distance corresponding to the size of the work, fingers extending toward one another formed on adjacent ends of the arms and forming a work support, guide means cooperating with the arms and forming therewith a work guiding chute, and means for vertically shifting the carrier comprising a piston secured thereto, a cylinder for the piston, conduits extending from opposite ends of the cylinder, a valve coupled to the other end of the conduits, a pressure source and an exhaust coupled to the valve, and an oscillatable plug in the valve having ports therein for alternately connecting the pressure source and exhaust with the conduits for alternately effecting a raising and a lowering of the carrier.
14. In a device of the class described the combination with a pair of opposed grinding and regulating wheels forming a grinding throat therebetween, a work rest blade subtending the grinding throat for supporting work while in engagement with the wheels, of means for placing in and removing work from the work rest blade comprising a vertically shiftable carrier, hydraulic means for effecting said shifting of the carrier comprising a pressure source and an exhaust, a conduit extending from opposite ends of the carrier, a valve comprising a body portion receiving one terminus of each of the conduits and the terminus of the pressure source and exhaust, an oscillatable cock carried by the body portion for alternately connecting the pressure source and exhaust with the conduits, means for feeding one of the wheels toward the other to feed the work into the grinding wheel and effect a stock removal therefrom, means for alternately oscillating the valve cock, and a lost motion connection between the wheel moving means and means for oscillating the cock whereby the said cock and wheel are moved in sequential order for first connecting the pressure source with one of the conduits for lowering the carrier to place an unfinished work piece on the work rest blade, then actuating one of the wheels toward the other to feed the work into the grinding throat, then retract said wheel at the completion of the grinding operation, and finally connect the pressure source to the other cylinder conduit for ejecting the finished work from the throat.
- In testimony whereof I affix my signature.
- CLEMENT BOOTH.
